ANDREW H. CANDEE, OF FOREST HILLS, PENNSYLVANIA, ASSIGNOR TO WESTINGHOUSE ELECTRIC & MANUFACTURING COMPANY, A CORPORATION OF PENNSYLVANIA.

CONTROL APPARATUS.

Application filed May 11, 1921. Serial No. 468,714.

My invention relates to devices adapted to rupture an electric arc when formed between two points, such as contact members of unit switches for controlling electric 5 motors or the like.

The object of my invention is to provide a blow-out magnet of improved character which will confine the path of an arc substantially within definite limits.

10 In the design of magnetic switches or contactors, it is customary to provide an arc shield of insulating material and a single blow-out coil having magnetic pole pieces to direct the electric arc away from parts 15 of the contactor or adjacent apparatus which might otherwise be injured thereby. It is well understood that the extreme heat from an electric arc will, in the course of a short time, disintegrate the arc chute at 20 points against which the arc is directed.

I propose to provide a substantial arcing horn of suitable current-conducting material for connecting the stationary contact member to one end of the blow-out magnet 25 coil. Current traversing the convolutions of the blow-out coil is reversed in its direction through the arcing horn, with relation to the direction of the current through the adjacent convolutions of the coil. The magnetic field induced by the current traversing the arcing horn has lines of magnetic force which are opposed to those induced in the field between the blow-out-coil pole pieces. By a suitable arrangement or relation of 30 these fields, it is possible to control the path of an electric arc and, incidentally, to avoid deterioration of the arc shield.

The single figure of the drawing is a side view, partially in section and partially in 40 elevation, of apparatus embodying my invention.

The engagement of stationary contact member 1 and movable contact member 2 is controlled by the switch plunger 3. An 45 arcing horn 4 is attached, at one end, to the stationary contact member 1 and is fastened at its other end to the blow-out coil 5. The other end of the blow-out coil is fastened to a bracket 6 mounted on an insulating base 7 50 which supports the entire switch structure. The blow-out coil is provided with a core 8 and pole pieces 9 engaging therewith. An arcing horn 10 is attached to contact member

2. An arc chute 11, of well known design, is provided.

55 It may be assumed that the contactor has been closed and that the current traversing the contact members 1 and 2 is directed from the bracket 6, in a direction indicated by the arrows, through the blow-out coil 5. 60 The current leaving the blow-out coil is directed through the arcing horn 4 and contact members 1 and 2. Upon interruption of the electrical circuit by the separation of contact members 1 and 2, the current traversing said members is directed through the arc which acts as a conductor and which behaves in the magnetic field of the blow-out magnet in a manner similar to an armature 65 conductor in the magnetic field of a motor. 70

The path of the arc is bowed and extends, as indicated by the dotted arrow line, from the arcing horn 4 to the movable contact member 2. The magnetic lines of force in the field between the pole pieces 9 are directed perpendicularly to the plane of the paper, assuming that the pole pieces lie in planes parallel to the plane of the paper. The magnetic field, induced by current in the arcing horn 4, comprises lines of magnetic force encircling the arcing horn in a clockwise direction with respect to the direction of the current, that is to say, lines of magnetic force are directed downwardly at the left and along the upper extension of 80 the arcing horn. At the intersection of these oppositely directed fields is a neutral zone. The path of the arc is extended outwardly to the left and upwardly under the influence of the field induced by the magnetic blow-out, but the upward movement of the arc is opposed by the field induced around the arcing horn and beyond the neutral zone. The combined action of 85 the two fields restricts the path of the arc and protects the upper section of the arc chute.

90 The length of the path of the arc depends upon the energy in the interrupted circuit. The lower arcing horn 10, acting as a conductor, induces a magnetic field opposite to the field of the arcing horn 4. The arc is directed away from the lower section of the arc chute, under the influence of that portion of the field not affected by the field of 105 the pole pieces 9.

The advantages of the structure which I have disclosed will be at once apparent, especially in the use of a single-coil blow-out magnet. With slight modifications, 5 this device may be adapted to various contractors of well known and standard design. The arrangement of parts illustrated is a matter of convenience and lends itself readily to modification without departing from 10 my invention.

I claim as my invention:—

1. An arc-rupturing device comprising, in combination, a plurality of contact members, arc horns carried by the contact members, 15 an arc chute substantially enclosing the arc horns, an electromagnet and pole pieces carried by the electromagnet and extending adjacent the sides of the chute, said pole pieces being disposed to effect the movement of an arc outwardly along the arc horns, one of 20 the arc horns extending beyond the pole pieces and being adapted to serve as a feed conductor for the corresponding contact member to develop a magnetic field in opposition 25 to the electromagnet to restrict the travel of an arc along said arc horn, thereby to protect the chute.

2. An arc-rupturing device comprising, in combination, a plurality of contact members, 30 arc horns carried by the contact members, an arc chute substantially enclosing the arc horns, an electromagnet and pole pieces carried by the electromagnet and extending adjacent the sides of the chute, said pole pieces 35 being disposed to effect the movement of an arc outwardly along the arc horns, one of the arc horns being extended beyond the pole pieces and adapted to serve as a feed conductor for the corresponding contact member 40 to develop a magnetic field in opposition to the electromagnet at a point adjacent the pole pieces, thereby to limit the travel of an arc along the arc horn.

3. An arc-rupturing device comprising, in 45 combination, a plurality of contact members, arc horns carried by the contact members, an arc chute substantially enclosing the arc horns, an electromagnet and pole pieces carried by the electromagnet and extending adjacent 50 the sides of the chute, said pole pieces being disposed to effect the movement of an arc outwardly along the arc horns, one of the arc horns being extended beyond the pole pieces and adapted to serve as a feed conductor 55 for the corresponding contact member to develop a magnetic field in opposition to the electromagnet to create a neutral point between the two magnetic fields at 60 a point near the pole pieces to restrict the travel of the arc along said arc horn.

4. An arc-rupturing device comprising, in combination, a plurality of contact members, arc horns carried by the contact members, an arc chute substantially enclosing the arc horns, an electromagnet and pole pieces carried by the electromagnet and extending adjacent the sides of the chute, said pole pieces being disposed to effect the movement of an arc outwardly along the arc horns, one of the arc horns being extended beyond the pole 65 pieces and adapted to serve as a feed conductor for the corresponding contact member to develop a magnetic field in opposition to the electromagnet to create a neutral point between the two magnetic fields at a point 70 near the pole pieces to restrict the travel of the arc along said arc horn, said arc horn being extended back on itself from substantially the point of the neutralized magnetic fields.

5. An arc-rupturing device comprising, in combination, a plurality of contact members, arc horns carried by the contact members, an arc chute substantially enclosing the arc horns, an electromagnet and pole pieces carried by the electromagnet and extending adjacent the sides of the chute, said pole pieces being disposed to effect the movement of an arc outwardly along the arc horns, one of the arc horns being extended beyond the pole 80 pieces, the outer end of the horn being curved back on itself and connected to a feed conductor, thereby to provide for the development of a magnetic field in opposition to the electromagnet at a point near the pole 85 pieces to restrict the travel of the arc along the arc horn.

6. An arc-rupturing device comprising, in combination, a plurality of contact members, arc horns carried by the contact members, an arc chute substantially enclosing the arc horns, an electromagnet and pole pieces carried by the electromagnet and extending adjacent the sides of the chute, said pole pieces being disposed to effect the movement of an arc outwardly along the arc horns, one of the arc horns being extended beyond the pole pieces, the outer end of the horn being curved back on itself and connected to a feed conductor to provide for the development of a magnetic field in opposition to the electromagnet at a point near the pole pieces and substantially where the arc horn begins to recede, thereby to restrict the travel of an arc along the arc horn.

In testimony whereof, I have hereunto subscribed my name this 29th day of April, 1921.

ANDREW H. CANDEE.
